Primary Examiner — Garth Rademaker(74) *Attorney, Agent, or Firm* — Flynn, Thiel, Boutell & Tanis, P.C.(57) **CLAIM**

The ornamental design for a developing device for a laser printer, as shown and described.

DESCRIPTION

FIG. 1 is a top front perspective view of a developing device for a laser printer showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.

The broken lines depict environmental subject matter only and form no part of the claimed design.
